UNITED STATES PATENT OFFICE.

RICHARD L. WILLIAMSON, OF OAKLAND, CALIFORNIA.

DESIGN FOR A TRACTOR.

55,225.

Specification for Design.

Patented May 18, 1920.

Application filed November 28, 1919. Serial No. 341,326. Term of patent 7 years.

To all whom it may concern:

Be it known that I, RICHARD L. WILLIAMSON, a citizen of the United States, and a resident of Oakland, county of Alameda, State of California, have invented a new, original, and ornamental Design for a Tractor, of which the following is a specification, reference being had to the accompanying drawings, forming part thereof in which—

Figure 1 is a side elevation of the tractor illustrating my new design.

Fig. 2 is a front elevation of the tractor.

Fig. 3 is a rear elevation of the tractor.

I claim:

The ornamental design for a tractor substantially as shown.

RICHARD L. WILLIAMSON.
